Primary Examiner — Elizabeth J Oswecki*(74) Attorney, Agent, or Firm* — Foley & Lardner LLP**CLAIM**

We claim the ornamental design for a 6 tier center support cake stand, as shown and described.

DESCRIPTION

FIG. 1 is a front perspective view of a 6 tier center support cake stand showing our new design;

FIG. 2 is a left side view thereof;

FIG. 3 is a right side view thereof;

FIG. 4 is a front view thereof;

FIG. 5 is a bottom view thereof; and,

FIG. 6 is a top view thereof.

The subject matter shown in dashed lines, and any surfaces of the design not shown, including interior surfaces, form no part of the claimed invention.

The pole is shown broken away in FIGS. 1-4 to indicate that no particular length is claimed.
